Des. 212,639
Patented Nov. 5, 1968

212,639

COVERED FOOD SERVING DISH

Paul K. Schilling, St. Paul, Minn., assignor, by mesne assignments, to Plastics, Inc., St. Paul, Minn., a corporation of Delaware

Filed Oct. 25, 1967, Ser. No. 9,165

Term of patent 14 years

(Cl. D44—15)

FIG. 1

FIG. 2

FIG. 3

FIG. 4

FIG. 5

FIGURE 1 is a top plan view of a covered serving dish, showing my new design;

FIGURE 2 is a sectional view on line 2-2 of FIGURE 1;

FIGURE 3 is a bottom plan view of the cover member;

FIGURE 4 is a reduced scale side elevational view of the covered food serving dish inverted from the position of FIGURE 2; and

FIGURE 5 is an enlarged scale fragmentary sectional view on the line 5-5 of FIGURE 4.

I claim:

The ornamental design for a covered food serving dish, as shown.
